PORTABLE FEMININE FOUNTAIN SYRINGE

Anne Houssein, New York, N.Y.

Application December 18, 1957, Serial No. 48,942

Term of patent 14 years

(Cl. D83—1)

FIG. 1

Fig. 1 is a front view of a portable feminine fountain syringe, showing my new design. The rear not shown, is substantially the same.

Fig. 2 is an enlarged top plan view thereof.

The stripes appearing on the front of the bag illustrated in broken lines, as viewed in Fig. 1, are intended to cover the entire area encompassed thereby.

The drawing is shaded to represent contrasting colored areas.

The essential features of my design reside in the portions shown in full lines.

I claim:

The ornamental design for a portable feminine fountain syringe, substantially as shown and described.
